Specification of Letters Patent.

Patented June 1, 1915.

Application filed February 20, 1914. Serial No. 819,981.

To all whom it may concern:

Be it known that I, FRITZ SCHRÖTER, a citizen of the German Empire, and resident of Wilmersdorf, near Berlin, Germany, have invented certain new and useful Improvements in and Relating to Devices for Working Weak-Current Installations, of which the following is a specification.

The object of the present invention is a process together with a device shown in several modifications for working weak current installations, *e. g.* bell installations, by means of storage cells or batteries, the consumption of the energy stored in the accumulators being automatically restored from time to time to a certain extent by connection with power or charging current lines, so that the storage cells can never be either over discharged or over charged. The connection of the accumulators to the power line is made through contacts operated by a relay placed in the weak current circuit, or in an auxiliary current circuit parallel thereto. This relay can, however, only be operated by proper connections after the discharge of a certain quantity of amere-hours from the accumulators; as long, however, as the accumulators are still sufficiently charged the relay is automatically cut out or short-circuited.

In the accompanying drawings, Figure 1 represents an installation of a bell circuit with means to charge the accumulator as the bell is operated; Fig. 2 shows a modification in which both sides of the charging current circuit are broken; Fig. 3 is a further modification showing resistances in both sides of the charging current circuit; Fig. 4 is a further modification showing means to connect and disconnect a condenser at the same time the charging current is connected and disconnected; Fig. 5 shows a modification of Fig. 1 in which means are used to limit the charging periods; Fig. 6 shows an arrangement utilizing changes in the specific gravity of the electrolyte to close the charging circuit; Figs. 7 and 8 show modifications in which a separate storage battery receives the charge, and in its turn charges the operating battery; Fig. 7^a is a modification in part, of Fig. 7; and Fig. 9 shows a modification in which an alternating current may be used as the charging current.

In Fig. 1 is shown diagrammatically a set

of connections wherein for the sake of simplicity the above mentioned charging or discharging limiter is at first omitted. The charging current line (continuous current, light or power line) is marked 1, 2; the conductor 2 is earthed. At 3, 4 a double line branches off to the side. The positive section receives a fuse 5, a series resistance 6 for reducing the tension, and then goes to the contact device 7, 8 which in a normal state is open and which can be closed by turning the relay lever 9. The condenser 10 is connected in parallel with 7, 8, in order to prevent excessive formation of sparks. The conducting part of the relay lever is connected with the positive pole of the operating storage battery 12 by way of 9 and the branching point 11; the return line to the heavy current network is by way of 13, 14. This branch has by connection to the earthed conductor 2 no pressure in relation to earth. The return line 14 to the charging current net-work is superfluous if another earth connection is possible in the vicinity of the device. From the branching point 11 the positive section 15 leads to the bell installation 16; naturally there may be any number of them connected in parallel to each other. The same applies to other kinds of weak current circuits; the bell installation will, however, be taken here all the way through as an example. The return line of the bell installation is marked 17. It does not conduct back direct to the negative pole of the battery, but through relay 18 electro-magnet 18 and thence by way of 13.

If the weak current circuit is closed by pressing any one circuit-closing contacts or push buttons 16' of the bell installation, the current flows from the positive pole of the battery by way of 11, 15 through the bell installation 16 by way of the bell and the push button, then back by way of 17, through the relay electromagnet 18, and finally by way of 13 to the negative pole of the battery. The relay is so adjusted that it functions throughout the duration of the closing of the circuit in the weak current circuit, although the bell as is well known produces an intermittent current. In other words it must possess a certain activity. The electromagnet 18 thus attracts its armature 19, so long as the weak current circuit is kept closed. Thereby, however, the contact 7, 8 is closed by tipping the relay lever around its center 110

of rotation 9, and now current flows from the heavy current line by way of the fuse 5, reducing-resistance 6, contact 7, 8, branching off at 11, one part going through the storage battery 12 and one part via 15 through the bell installation. By means of the first partial current the storage battery 12 is charged, and by the latter the bell installation is worked and the electromagnet 18 more strongly excited. The return line is from 12 via 13, 14; from 16 via 17, 18, 14. If the contact or push button 16' placed in the weak current circuit is released the current in the relay is interrupted, the relay 15 armature is released, the contact 7, 8 again opened and thus the heavy current line is cut out, whereby also the charging of the storage battery 12 ceases.

It would be possible to choose the size of the resistance 6 in such a manner that the current permitted to pass is just strong enough to exactly compensate the consumption of current from the battery for each time that the weak current circuit is cut in. However, the consumption is by no means always regular, particularly in the case of weak current circuits with variable load. It is therefore an essential part of the invention that charging and discharging of the storage battery are regulated by special devices. At the same time the size of the resistance 6 which is to be included in the charging current circuit is such that the accumulators at each closing of the circuit 35 receive more current than they give off, in other words would necessarily become more and more strongly charged if a final limitation of this process did not take place. This can be regulated in a well known manner by any kind of charge-limiting device, a suitable arrangement being shown in Fig. 5. The connections are the same as in Fig. 1. A glow lamp can be used to advantage as reducing-resistance 6^a in the power or charging current circuit, as shown in the figure. In the branch circuit of the storage battery 12^a a charging limiter is cut in, consisting of a suitable vessel 26^a, which is divided into anode compartment and cathode compartment by a partition reaching up to a certain height or by a diaphragm. Both contain quicksilver as electrodes, to which the current is conducted from below by means of inserted wires. The electrodes are coated with a quicksilver salt solution, which is indicated by 27^a. The chemical composition of the electrolyte is of no interest here; it can be chosen according to requirements and be provided with admixtures. A suitable electrolyte is a solution of mercuric chlorid in hydrochloric acid. With the cathode compartment (contemplated in the charging direction of the current) communicates a standing tube which enters the main vessel 60 above the level of the electrolyte and thus

has always the same gas pressure as the latter. In the tube is situated a short-circuit contact 25^a, which is electrically connected at 24^a with the return line 17^a. The height of the quicksilver in the tube is so chosen that the contact 25^a is open when the operating storage battery is discharged to the lower admissible limit. When the charging current flows into the battery and through the cell 26^a, quicksilver is deposited on the cathode, while quicksilver is dissolved at the anode. The quicksilver thus increases in mass and volume in the cathode compartment; and also the quicksilver level in the tube will rise in the same measure as the metal in the cathode compartment gains in height. After a sufficient quantity of ampere-hours has flowed through the limiter as charging current of the accumulators to deposit enough quicksilver to short-circuit the contact 25^a, on the next operation of the weak current circuit the current will not be conducted back through the relay electromagnet 18^a, but direct by way of 24^a, 25^a to the battery; the relay therefore will not function and the charging current installation will not be cut in until, by means of the discharging current of the battery, so much quicksilver has been dissolved in what is now the anode compartment of the limiter situated to the right, and has been deposited at the left that the contact 25^a has been interrupted by a corresponding fall of the quicksilver in the tube. Then the relay functions again; and by connection with the charging current line a new charging period begins for the storage battery.

Under certain circumstances it may be advantageous to utilize the gradual increase in volume of the quicksilver situated in the cathode compartment during the charging period of the storage battery for gradually raising a float, which in its highest position brings two contacts which are placed in shunt with the relay electromagnet into connection with each other in some manner, without these contacts making electrical connection with the quicksilver of the limiter cell. The contacts, which short-circuit the electromagnet windings so that it cannot be excited, are to be completely insulated from the quicksilver. This measure is used in the connection plans of Fig. 7, 7^a and 8 referred to later.

Fig. 6 shows how the change in the accumulator density of the electrolyte, which is proportional to the amount of electricity which has flowed through, can be utilized for releasing the short-circuit of the relay. It is known that the electrolyte of an accumulator becomes denser during charging, and this fact has already been utilized in order to limit the charging condition of the battery by means of the gradual rise of a float constructed on the principle of the

hydrometer, in which the float makes some contact or other. This well-known method is used in Fig. 6 for the purpose of the invention. In this figure 28⁶ represents a storage cell with the plates 29⁶ and the electrolyte 30⁶. In a special compartment of the vessel 31⁶ is situated the hydrometer 32⁶ which functions as a float and which on the charging of the battery rises and finally 10 closes the short-circuit contact 33⁶ which short-circuits the windings of the relay electromagnet.

Particular qualities of the connection are shown by Figs. 2, 3, 4. Figs. 2 and 3 refer 15 to cases in which a fixed connection of the weak current with the heavy current line is not admissible in any place when putting up the apparatus, as shown in Figs. 1 and 5 at 13 and 14 and 13⁵, 14⁵. This might 20 be the case if both conductors of the heavy current line have a tension different from zero potential or earth. The condensers and the charging limiters are omitted for the sake of simplicity. Both sections of the 25 heavy current line can then be conducted to contacts 7², 7²¹ and 7³, 7³¹, which in the normal condition of the weak current circuit are open and are only connected to the weak current circuit by the attraction of the 30 relay armature 19², 19³ by means of the contact springs 8², 8²¹, 8³, 8³¹. If one heavy current conductor has a certain positive, and the other an equally great negative tension to zero or earth, it is advisable to place in 35 circuit the resistance 6², 6³, 6³¹ and fuses 5², 5³, 5³¹ in both heavy current sections. In the figures glow lamps are chosen as resistances.

In Fig. 4 in which the charging limiter is also omitted for the sake of simplicity, 40 the condenser 10⁴ is not firmly connected with the positive branch of the storage battery situated in the weak current circuit, as is shown in Figs. 1 and 5, since on the disruptive discharge of the condenser the 45 battery might become charged to an unlimited extent. One line to the condenser branches off at 21⁴ or at 20⁴ from the power current section, by preference from the latter in case the resistance 6⁴ possesses considerable self-induction. The line connecting the condenser goes to the easily movable contact arm 22⁴, which on the rising of the relay lever first makes electric connection 50 with the weak current circuit at 23⁴. Inversely the connection of 22⁴ and 23⁴ continues after the opening of the contacts 7⁴, 8⁴. The condenser thus receives the high tension and makes 7⁴, 8⁴ free from sparks. In the normal position of the relay lever, 55 after its complete return, the connection 22⁴, 23⁴ is, however, broken. In accordance with the invention it is also possible to proceed in such a manner that no connection between the charging current line, at least 60 between the parts of it which are under

pressure with relation to the earth, and the weak current line, does not take place even during the charging of the storage battery. Fig. 7 illustrates this case. It is assumed in the first place that the negative charging 70 current conductor 14⁷ is earthed. The operating storage battery 12⁷ serves as the working current source of the weak current circuit. A second or supplementary battery 34⁷ is connected in series with a charging limiter 75 26⁷ and the relay formed with the help of the contacts 35⁷, 36⁷, in such a manner that in the normal position, when the weak current circuit 15⁷, 17⁷ is open and the relay does not function, the positive pole of 34⁷ 80 is connected via contact 35⁷, 9⁷ and 11⁷ with the similar pole of 12⁷. As the negative battery poles are also connected with each other via 26⁷, 13⁷ (an equalizing resistance can also be connected in series with 12⁷), both 85 batteries are now simply connected in parallel. If the contact is closed in the weak current circuit, and the windings of 18⁷ are not short-circuited by limiter 26⁷, the electromagnet is excited, the armature 19⁷ is 90 attracted, the battery 34⁷ is thereby disconnected from the weak current circuit and connected to the charging current circuit at 36⁷, as is obvious without further explanation from the figure. Supplementary battery 34⁷ is thereby charged, without the weak current circuit having connection with 36⁷. If the contact in the weak current installation ceases, 19⁷ is released, the battery 34⁷ is disconnected from the charging current circuit and at the same time is closed through 37⁷ on battery 12⁷. The operating battery 12⁷ thereby receives a part of the charge of supplementary battery 34⁷ and 100 remains constantly ready for working. If 105 battery 34⁷ is charged to its full capacity the charging limiter 26⁷ short-circuits the electromagnet 18⁷ (as shown in Figs. 5 and 6) until battery 34⁷ is sufficiently discharged 110 to cease operating the limiter 26⁷.

Fig. 7^a shows the case in which both power current conductors have high pressure with regard to earth contacts 35^a and 36^a resemble 35⁷ and 36⁷, but are connected to the negative wire. There is also the complete 115 disconnection of the weak current circuit, even during the charging on the negative side. The same idea can also be carried out—see Fig. 8—in such a manner that the charging limiter 26⁸ places a relay 18⁸ in 120 circuit at the lower discharge limit, the relay not being connected in series with the weak current line, but parallel to it and to the battery 12⁸; if necessary with the equalizing resistance 40⁸ placed in circuit. If 34⁸ 125 is discharged to the bottom limit, 18⁸ is placed in circuit and excited from the battery 12⁸. The relay armature actuates a bipolar switch 37⁸, 37⁸¹ in such a manner that the connection with the weak current line is 130

broken at the contacts 39^a, 39^b and made instead at 38^a, 38^b with the charging current line, whereby 34^a is charged until the charging limiter comes into operation.

5 Then by releasing the relay armature the storage battery 34^a is again connected in parallel to 12^a. Any current that may be required in the weak current line is supplied by battery 12^a during the disconnecting and 10 charging process of battery 34^a.

In the case of alternating current it is possible to proceed in accordance with the connections hitherto indicated in their various forms of execution. It is only necessary 15 to place in the charging circuit a valve cell or rectifier cell in a suitable manner in the power current line immediately after the reducing-resistance (lamp), so that only impulses of the alternating current flowing 20 through the power current line are allowed in pass in the direction in which the storage battery is charged. It is, however, better for this purpose first to step down the alternating current to a lower pressure. A connection suitable for this purpose, in which no-load losses of the transformer do not take place, is shown in Fig. 9, the charging limiter being omitted. The line 3^a, 4^a branches off from the heavy current line 41^a, 42^a 25 which conducts the alternating current. Through the operation of the relay 18^a on contact being made in the bell installation 16^a the contact 43^a is connected with 44^a, and the alternating current flows through the 30 primary winding 45^a of the transformer, which is provided with parallel condenser 10^a. The current of the secondary winding 46^a goes partly through the weak current network via 15^a, 17^a, 18^a, 24^a, 13^a, 53^a and 35 40 back through the condenser 47^a which permits alternating current to pass; the positive current impulses within the meaning of the figure, which charge the accumulator, also go without hindrance from 11^a via 12^a, 45 resistance 40^a and through the permeable valve cell 52^a (rectifier cell) in the direction of the arrow. To actuate the weak current installation on placing a contact in circuit the current must flow through the battery 50 12^a in the opposite direction to the arrow. As the valve cell 52^a, however, would not permit this, the following arrangement is made. In the normal position, when the relay armature is released, the resistance 40^a 55 and the valve cell 52^a are shunted by a branch line 49^a, 50^a, as well as the contact device 48^a, 51^a, and the current can flow without hindrance to operate the bell and relay. When the relay lever has tipped all 60 most quite round through the attraction of the armature 19^a, the shunt circuit will be opened shortly before the closing of 43^a, 44^a by 48^a, 51^a, so that the valve cell can come

into operation for charging the battery. The condenser 47^a, which does not permit 65 direct current to pass, prevents in a normal position the battery 12^a from becoming discharged by way of the secondary winding 46^a of the transformer. It can be replaced by an interruptor-contact which is open in 70 the normal position and which is also governed by the relay.

Devices by means of which an auxiliary current source and relay prevent the no-load losses of transformers, are known, but the 75 arrangement described in the present invention varies from others heretofore used, by the fact that there is here shown means in the same circuit for automatically charging the source of auxiliary current. 80

In so far as condensers are adapted for replacing storage cells by receiving and giving off charging energy, they can be used in the connections designated above instead of such cells. 85

What I claim is:—

1. A system of operating weak-current installations by means of storage batteries, comprising a storage battery, a relay, a charging circuit, means to connect said battery with said charging circuit when the relay is energized, and means to short-circuit said relay when the charge-content of said battery exceeds a predetermined value. 90

2. A system of operating weak current installations by means of storage batteries comprising a weak current circuit, a charging circuit, two storage batteries one connected constantly in the weak current circuit and normally in parallel with the second, an automatic switch in the weak current circuit adapted to control the connection of the two batteries with each other and the connection of the second battery with the charging circuit during the discharge of the 100 first battery. 105

3. A system of operating weak current installations by means of storage batteries comprising a weak current circuit, a charging circuit, two storage batteries one connected constantly in the weak current circuit and normally in parallel with the second, an automatic switch in the weak current circuit adapted to control the connection of the two batteries with each other and the connection of the second battery with the charging circuit during the discharge of the first battery and a charge limiter connected in the circuit of the second battery. 115

In testimony whereof I affix my signature 120 in presence of two witnesses.

FRITZ SCHRÖTER.

Witnesses:

JEAN GRUND,
CARL GRUND.

It is hereby certified that in Letters Patent No. 1,141,836, granted June 1, 1915, upon the application of Fritz Schröter, of Wilmersdorf, near Berlin, Germany, for an improvement in "Devices for Working Weak-Current Installations," errors appear in the printed specification requiring correction as follows: Page 2, lines 120-121, strike out the word "accumulator"; same page, line 121, before the word "electrolyte" insert the word *accumulator*; and that the said Letters Patent should be read with these corrections therein that the same may conform to the record of the case in the Patent Office.

Signed and sealed this 17th day of August, A. D., 1915.

[SEAL.]

J. T. NEWTON,

Acting Commissioner of Patents.
